UNITED STATES PATENT OFFICE.

WILLIAM A. SMITH, OF EASTON, PENNSYLVANIA, ASSIGNOR TO INGERSOLL-RAND COMPANY, OF JERSEY CITY, NEW JERSEY, A CORPORATION OF NEW JERSEY.

MOUNTING FOR ROCK-DRILLS.

1,347,185.

Specification of Letters Patent. Patented July 20, 1920.

Application filed March 22, 1920. Serial No. 367,939.

To all whom it may concern:

Be it known that I, WILLIAM A. SMITH, a citizen of the United States, residing at Easton, in the county of Northampton and 5 State of Pennsylvania, have invented a certain new and useful Improvement in Mountings for Rock-Drills, of which the following is a specification.

This invention relates to an improved 10 mounting for rock drills by means of which the drill body or casing may be conveniently secured upon a cradle adapted to be slidably mounted in a drill shell of the usual or suitable construction.

15 The objects of the invention are to enable the drill body or casing to be simply and rigidly mounted and capable of being removed when desired, with the minimum of parts requiring adjustment and afford 20 simple means by which continuous side bolts are utilized for clamping the front and back heads of the rock drill to the cylinder casing and for clamping said cylinder casing and heads to the guide or cradle, thus 25 obviating separate bolts for the two functions.

The invention is illustrated in one of its preferred forms in the accompanying drawings in which—

30 Figure 1 is a side elevation of so much of a rock drill as will serve to show the invention, and

Fig. 2 is a detailed perspective view of the guide or cradle.

35 Referring to the drawings, A represents a drill cylinder casing for a drill which may be of the hammer type for illustrative purposes. Such a type of drill is conveniently mounted in a cradle B of the general form 40 shown in Fig. 2, which cradle is adapted to slide longitudinally in a shell (not shown). In this type of drill, the cylinder casing A may be provided with the usual front head C adapted to receive the drill steel D and its 45 operative parts, and may also be provided with a back head E forming a closure for the cylinder casing A.

Side bolts are usually provided for holding the front and back heads to the cylinder 50 casing and separate means have been utilized for securing the parts of the drill casing to a cradle B. In accordance with the present invention however, I have designed an improved and simplified construction in

which one set of side bolts clamp the parts of 55 the drill casing to each other and to the cradle.

The cradle is formed in this instance with the body portion F having the longitudinal flanges or guides G for slidably engaging a 60 shell, and is also provided with the outwardly extending pairs of arms H and J within which the drill body or casing is adapted to lie in assembled position as shown in Fig. 1. The arms H and J are 65 provided with apertures K to receive the side bolts L having the heads O and tightening nuts P.

The front head C is formed with holding lugs Q at each side, those on one side only 70 being shown for simplicity, and the back head E is also provided with holding lugs R at each side, the bolts L being adapted to pass through said lugs when the apertures K in the guide arms H and J are alined with 75 said sets of holding lugs. The cylinder casing is preferably formed with guide lugs S at each side in alinement with the holding lugs on the front and back heads.

When the parts are assembled as in Fig. 80 1 and the bolts are tightened, the cylinder casing, front and back heads and the cradle are all securely clamped together. For convenience of assembling and demounting, the guide arms H preferably lie forwardly of 85 the holding lugs Q and the guide arms J preferably lie forwardly of the holding lugs R.

I claim—

In a rock drill, a cylinder casing having 90 front and back heads, holding lugs at each side of the front and back heads, guide lugs at each side of the cylinder casing in line with the said holding lugs, a cradle for the rock drill provided with a body portion having 95 guides and also having supporting arms adapted to lie opposite the said holding lugs on the front and back heads, and continuous side bolts adapted to extend through the said supporting arms and holding and guide lugs at each side of the rock drill and means 100 for tightening the bolts to clamp the cylinder casing and front and back heads to each other and to the said cradle.

In testimony whereof I have hereunto set 105 my hand.

WILLIAM A. SMITH.
